H. F. Lewis

UNITED STATES PATENT OFFICE.

SIMON LAKE, OF OCEAN CITY, NEW JERSEY.

MECHANICAL MOVEMENT.

SPECIFICATION forming part of Letters Patent No. 363,472, dated May 24, 1887.

Application filed August 5, 1886. Serial No. 210,111. (No model.)

To all whom it may concern:

Be it known that I, SIMON LAKE, a citizen of the United States, residing at Ocean City, in the county of Cape May and State of New Jersey, have invented certain new and useful Improvements in Mechanical Movements; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to mechanical movements; and the object of the device is to provide a mechanical device which may be readily and simply operated to apply the power to the driven shaft in such a manner 20 that the strain or reaction from the driven parts will be prevented from affecting the prime motor.

To this end the novelty consists in the construction, combination, and arrangement of 25 parts, as will be more fully hereinafter described, and particularly pointed out in the claims.

In the accompanying drawings the same letters of reference indicate like parts of my 30 invention.

Figure 1 is a top plan view of my mechanical movement. Fig. 2 is a sectional view on the line $x-x$, Fig. 1; and Fig. 3 is a modification of the same, the working parts being the 35 same; but the handle or lever is extended on each side of the fulcrum, so that both handles may be used for operating, instead of one, as in the first instance.

A represents a stationary cylinder, which is 40 suitably secured in a rigid position to any convenient part of the frame.

B represents the end of the shaft or other part to which the power is to be applied, and said end B turns freely in the cylinder A.

45 C C are taper keys adjustably secured in slots $c-c$ by means of screws $c'-c'$, and D D are bearing-blocks, likewise located in said slots and having their forward ends semicircular in shape to correspond to and form seats for the 50 friction-pawls E E, the outer curved ends of which form the periphery of a circle at a tan-

gent to the inner surface of the cylinder A. These two pawls E E are connected by a spiral spring, e, which tends to draw them together until their adjoining ends or that point of 55 their outer ends marked a is in contact with the inner surface of the periphery of the cylinder A.

F is a lever pivoted or fulcrumed by the screw-bolt f to the end of the shaft B, and so 60 extending diametrically a suitable distance across and beyond the outside of the cylinder.

G G are lugs on the shaft B, between which the lever F plays, and I I are arms on the lever, which alternately engage with and operate the pawls when the lever is moved to the right or left. The length of the arms is such that when the lever is hard against one of the lugs G the arm on that side of the lever will 65 push its pawl forward to disengage it from 70 the cylinder, as shown in dotted lines in Fig. 1.

The operation of the device is as follows: The parts being in the position shown in Fig. 1, the shaft is securely locked against any lateral movement in the cylinder by reason of 75 the pawls engaging the same. If, however, the shaft is to be moved, say, in the direction of the arrow, the lever is pushed in that direction, and the arm on that side first pushes the forward pawl ahead, so as to release it from 80 the cylinder, and the lever then comes in contact with the forward lug, and of course the shaft is moved forward as far as necessary. At the same time the forward pawl is released the rear pawl is undisturbed, thereby locking 85 the shaft against any backward strain, and it will be observed that as the shaft is intermittently moved forward the rear pawl follows up and locks the shaft in whatever position it may be left. It will also be observed that 90 should the strain on the shaft be reversed or come in the opposite direction the forward pawl would then lock it in the same manner as in the first instance. Of course the lever and shaft may be moved in the opposite direction to that indicated by the arrow.

The modification, Fig. 3, shows the lever extending across and on both sides of the shaft, whereby it may be the more conveniently grasped by both hands for operating.

100 From the above it will be seen that the device is extremely simple, and can be employed

wherever a crank or lever power is required to sustain a weight or pressure in one or both directions without the strain coming on the lever—as, for instance, in steering apparatus, 5 capstans, windlasses, and all forms of hoisting devices; also, for the steering gear of bicycles and tricycles, road-engines, and, in fact, in any class of machinery using a power-controlling device. Of course it will be seen that 10 should the outer surface of the pawls wear they may be adjusted outwardly by means of the taper key and screw. This can be done either by forcing the wedge nearer the lower end of its socket or by providing its upper end with 15 a slot through which the screw is passed.

Having thus fully described my invention, what I claim, and desire to secure by Letters Patent of the United States, is—

1. The combination, with a cylinder or casing, of a shaft located within said cylinder, and mechanism, as described, whereby the said shaft may be freely moved in either direction and automatically locked against any reactionary strain or pressure, as set forth.
- 25 2. The combination, with the cylinder, the shaft, and the pawls or detents carried by the

shaft, of the lever arranged to operate the pawls and shaft, as set forth.

3. The combination, with the cylinder, of the shaft provided with lugs, the pawls, a connecting spring, and the lever fulcrumed to the shaft, so as to be capable of a movement in advance of the shaft, and arms arranged to operate the pawls before said lever operates the shaft, as set forth.

35 4. The combination, with the lever, the cylinder, and the shaft, of the pawls adjustably held in the end of the shaft, whereby they may be moved toward the cylinder, substantially as set forth.

40 5. The combination of the cylinder, the shaft having the lugs, the lever, the pawls, the bearing-blocks, and the tapered keys, all arranged and operating substantially as herein described and shown.

45 In testimony whereof I affix my signature in presence of two witnesses.

SIMON LAKE.
